UNITED STATES PATENT OFFICE.

ABEL D. TYLER, JR., OF BROCKTON, MASSACHUSETTS, ASSIGNOR TO THE
TYLER HINGED LAST COMPANY, OF SAME PLACE.

DESIGN FOR A HINGE.

SPECIFICATION forming part of Design No. 30,020, dated January 17, 1899.

Application filed August 4, 1898. Serial No. 687,752. Term of patent 7 years.

To all whom it may concern:

Be it known that I, ABEL D. TYLER, Jr., of Brockton, in the county of Plymouth and State of Massachusetts, have invented and produced a new and original Design for Hinges, of which the following is a specification, reference being had to the accompanying drawings, forming part thereof.

Figure 1 is a perspective view of a hinge containing my design; and Figs. 2 and 3 are lengthwise sectional views at lines 2 2 and 3 3, respectively, of Fig. 1.

As shown in the drawings, the leading or material feature of my design consists of the rectangular shape of the bar-like shanks of the hinge and the straight shoulders of the single-eared member at the base of the ear. One bar-like shank a of the hinge has two ears a' , between which the single ear a^2 of the

other bar-like shank a^3 is confined by the pin-hole a^4 . The shoulders a^5 of the single-eared shank a^3 at the base of the ear are straight across the member a^3 , there being a shoulder a^6 at each of two opposite sides of ear a^2 and at right angles to said sides. Each shank is provided with a pin-hole a^6 .

What I claim is—

The design for a hinge, as herein shown and described.

In testimony whereof I have signed my name to this specification, in the presence of two subscribing witnesses, on this 30th day of July, A. D. 1898.

ABEL D. TYLER, JR.

Witnesses:

E. A. ALLEN,
EDWARD S. BEACH.
